UNITED STATES PATENT OFFICE.

JOSEPH E. STRAKER, JR., OF ATTLEBORO, MASSACHUSETTS, ASSIGNOR
TO WATSON AND NEWELL COMPANY, A CORPORATION OF RHODE
ISLAND.

DESIGN FOR A HANDLE FOR SPOONS, FORKS, OR SIMILAR ARTICLES.

SPECIFICATION forming part of Design No. 36,928, dated May 24, 1904.

Application filed April 28, 1904. Serial No. 205,423. Term of patent 7 years.

To all whom it may concern:

Be it known that I, JOSEPH E. STRAKER, Jr., a citizen of the United States, residing in Attleboro, in the county of Bristol and Commonwealth of Massachusetts, have invented a new, original, and ornamental Design for the Handle of a Spoon, Fork, or Similar Article, which is illustrated in the accompanying drawings, forming part of this specification.

Figure 1 shows the obverse and Fig. 2 the

reverse face of my design as embodied in the handle of a spoon or fork.

What I claim is—

The ornamental design for the handle of a spoon, fork or similar article as shown.
